CLAIM

The ornamental design for a back scratcher as shown and described.

DESCRIPTION

FIG. 1 is a perspective view of a back scratcher showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view of the back scratcher;

FIG. 8 is an enlarged bottom plan view of the back scratcher;

FIG. 9 is a perspective view of the back scratcher in another state;

FIG. 10 is an enlarged view of a portion of the back scratcher shown within the area designated as 10 in FIG. 1;

FIG. 11 is an enlarged view of a portion of the back scratcher shown within the area designated as 11 in FIG. 2;

FIG. 12 is an enlarged view of a portion of the back scratcher shown within the area designated as 12 in FIG. 3;

FIG. 13 is an enlarged view of a portion of the back scratcher shown within the area designated as 13 in FIG. 4; and,

FIG. 14 is an enlarged view of a portion of the back scratcher shown within the area designated as 14 in FIG. 5.

The dash-dash broken lines in the drawings depict portions of the back scratcher that form no part of the claimed design. The dot-dash broken lines represent boundaries of the enlarged portions and form no part of the claimed design.

1 Claim, 14 Drawing Sheets
